MOBILE MANIPULATIVE TOY FOR CHILD
PARTICIPATION
Kenneth G. Neils, Box 267, Bigfork, Mont. 59911
Filed Nov. 28, 1966, Ser. No. 597,360
6 Claims. (Cl. 212—65)

This invention relates to a toy of the "sit-on" type in which the child while seated on the toy may selectively manipulate the toy to perform various operations and, to a degree at least, participate in the operations of the toy responsive to such manipulation.

It is an object of this invention to provide in a toy as aforesaid, a rotatable platform on which the child is seated and from which he can manipulate a hoisting device at will and by a similar manipulation turn the platform including his seat to a full 360 degrees in either direction.

It is a further object of this invention to provide in a toy as aforesaid, pedal-operated means with means optionally for connecting a pedal-driven shaft to a hoisting drum or to rotation of the platform on which the child is seated through a full 360 degrees in either direction.

It is a further object of this invention to provide, in a toy as aforesaid, means for safely seating the child and for mobility of the toy as a whole.

The above and other objects will be made clear from the following detailed description taken in connection with the annexed drawings, in which:

FIGURE 1 is a side elevation of the toy as a whole;
FIGURE 2 is a plan view of the toy shown in FIGURE 1;

FIGURE 3 is a view on the line 3—3 of FIGURE 1;
FIGURE 4 is a view partly in section taken on the line 4—4 of FIGURE 1;

FIGURE 5 is a view partly in section taken on the line 5—5 of FIGURE 4; and

FIGURE 6 is a view partly in section taken on the line 6—6 of FIGURE 4.

The current vogue for "sit-on" toys goes beyond the older concept of sitting on the toy while propelling it in the manner of a kiddie car. The current vogue calls for a child to be able not only to sit on the toy but to direct its operations from his sitting position. It is well known that children enjoy emulating the activities of adults and this enjoyment is greatly increased if there is an actual participation in the activity which is simulated and the enjoyment is greatly increased with any increase in the verisimilitude of an activity. This is the principle on which the toy of this invention is based.

Referring now to FIGURE 1, the toy comprises a base portion 10 which, optionally, may be mounted on wheels 12. A platform 14 is pivoted at 16 (FIGURES 2 and 3) to the base 10 and is supported by a pair of idler rolls 18 and a pair of drive wheels 20 and 22, all journaled in or on the platform 14. A frame 24 having side walls 26 is secured to the platform 14 and is considered a part thereof. A boom 28 is pivoted at 30 to the platform 14 and has a pulley 32 at its free end. The boom 28 is held in predetermined angular position by a cord or cable 34 which is anchored to a post 36 secured to the casing 24.

Journaled between the side walls 26 of the casing 24 is a shaft 38 carrying a drum 40. The drum 40 has a grooved wheel 42 at one end and a grooved wheel 44 at the other. It carries a cable or cord 46 which runs over the pulley 32 on the boom 28 and terminates in a load-attaching device 48. This is shown as a hook but it may comprise a bucket, a clam shell or any other suitable load-attaching device.

2

Also journaled between the side walls 26 of the casing 24 is a shaft 50 on which are formed a pair of cranks and pedals 52, accessible to the child who is operating the device. The shaft 50 constitutes a drive shaft and, of course, in a more elaborate model the pedals and cranks 52 could be replaced by a suitable motor. A double pulley 54 is secured to the shaft 50 and one groove of the pulley 54 carries a belt 56 which passes around the wheel 44 of the drum 40, thence back to the pulley 54. This transmits power from the shaft 50 to the drum 40 for hoisting operations. The casing 24 has an intermediate wall 58 and a shaft 60 is journaled between the wall 58 and the adjacent wall 26. A seat 62 (FIGURE 6) is supported between the intermediate wall 58 and opposite wall 26 and, as will be observed in FIGURE 6, offers the occupant of the seat easy access to the pedals 52 and to the assortment of levers shown in FIGURE 6 which will presently be described.

Referring now to FIGURE 4, in which the seat portion 62 has been removed, there is shown a shaft 64 in advance of the seat and overlying the shaft 50, the shaft 64 being journaled in the side walls 26. Under the rear portion of the seat 62 a shaft 66 is journaled in the side walls 26 and extends therebetween. A lever 68 is secured to the shaft 64 just in front of the seat portion 62 and a lever 70 is secured adjacent the opposite end of the shaft 64. The lever 70 is pivoted to a link 72, the other end of which is pivoted to a lever 74 which is fixed on the shaft 66. As will presently be described, this lever 68 which is on the operator's left controls the swing motion.

A second motion lever 102 to the right of the driver controls the hoist. This lever 102 is affixed to a sleeve 104 which is freely rotatable on the shaft 64. A lever 106 is affixed to the sleeve 104 and has its free end pivoted to a link 108. The opposite end of the link 108 is pivoted to an arm 72 fixed to a sleeve 110 journaled on the shaft 66. A second arm 76 is fixed to the sleeve 110 and has at its free end a pulley 78 bearing on the belt 56. When the lever 102 is pulled rearwardly, it rocks arms 106 and 74 (through link 108) forwardly (as shown in FIGURE 5) and thereby rocks the arm 76 upwardly to engage the pulley 78 with belt 56 and begin hoisting action of the drum 40.

When the drum 40 has hoisted the attached load to the desired height, it is always desirable to stop hoisting action of the drum 40 but maintain the drum against unwinding until the platform and boom can be swung to another position whereupon the load is lowered back to the floor. This braking effect is accomplished by means of a handle 80 secured to the shaft 60. The crank 82 is also secured to the shaft 60 and is pivoted to a link 84 which, in turn, is pivoted to a lever securely attached to a sleeve 85 journaled on the shaft 66 (immediately adjoining the sleeve 74). Brake band 86 extends from a pivoted connection with the sleeve 85 around the wheel 42 of the drum 40 and thence to a bracket 88 secured to the platform 14. This mechanism permits holding and controlled lowering of the load while the drum 40 is effectively disconnected from the belt 56. Inasmuch as a toy of this type is capable of handling loads larger than the child should attempt to use, it may be desired to provide a suitable form of slip clutch between the drum 40 and the wheel 44, thus limiting the maximum load which can be handled by the drum 40. It was not deemed necessary to show such a slip clutch since its use is optional and its form merely a matter of selection from the prior art.

From a standpoint of childhood enjoyment, one of the most important aspects of the present invention involving a sit-on type of toy is the project of swinging the carriage relative to the base portion and as previously noted, this

may be accomplished in either direction for as many degrees as desired. This swinging function is accomplished as will now be described.

As best shown in FIGURE 4, the drive wheel 20 is mounted on a stub shaft 21 secured to the adjacent side wall 26 while the drive wheel 22 is mounted on a stub shaft 23 secured to its adjacent side wall 26. A belt 90 connects the drive wheel 20 to a pulley 92 secured to a shaft 94 which is journaled in the walls 26. Similarly, the drive wheel 22 is connected by a belt 96 to a pulley 98 which is also secured to the shaft 94. A drive pulley 100 is also secured to the shaft 94 and is connected by a belt 102 to a second groove in the pulley 54 on the drive shaft 50. Now it is clear that if the shaft 50 is rotating counterclockwise and this is preferred, the shaft 94 will also rotate counterclockwise and so will the pulleys 92 and 98, as well as the drive wheels 20 and 22. Despite the fact that the wheels 20 and 22 rotate in the same direction about their own axes, if power is applied to the wheel 20 and not to the wheel 22, the platform 14 and its associated parts will rotate relative to the base 10 about the pivot 16 in a clockwise direction, as viewed in FIGURE 4, while if the wheel 20 be idle and power applied to the wheel 22, the same rotation will occur but in a counterclockwise direction, as viewed in FIGURE 4.

As previously noted, the lever 68 provides a unitary means for selection as between wheels 20 and 22 and therefore as between clockwise and counterclockwise rotation, the platform 14 about the pivot 16, the following means have been provided.

The "swing" lever 68 is mounted ahead and to the left of the driver and within his reach and as viewed in the several figures is in its neutral position. As previously noted, the lever 68 rocks the shaft 64 and, through link 72 and lever 74, rocks the shaft 66. Pushing forward on the hand lever 68 therefore results in a clockwise rotation of the shaft 66, while a rearward pull on the hand lever 68 results in a counterclockwise rotation of the shaft 66. Also secured to the shaft 66 for rotation therewith is a lever 112 adjacent the drive wheel 20. The lever 112 carries a pulley 114, best shown in FIGURE 6. This pulley lies below and is engageable with the belt 96 to bring power from the shaft 94 to drive wheel 20. Also secured to the shaft 66 for rotation therewith is the lever 116 located adjacent the drive wheel 22 and carrying a pulley 118 which lies below and is engageable with the belt 96 whereby to tighten the belt and deliver power from the shaft 94 to the drive wheel 22. Accordingly, the platform 14 may be rotated about the pivot 16 either clockwise or counterclockwise, as viewed in FIGURE 4, depending on whether the hand lever 68 be pushed forward or pulled back, thereby engaging one or the other of the drive wheels 20 and 22.

It will be seen from the foregoing that the present device is a most unusual and educational toy. By providing a source of power from foot pedals, more actual power is available than normally would be the case where motive power as such is supplied by hand. Moreover, since motive power is dependent on the feet and not on the hands, both hands are available for manipula-

tion of two one-way levers, namely, 102 and 80, and one two-way lever, namely, 68. It is possible, therefore, for the child while his feet are occupied with the pedals to develop a considerable degree of manual dexterity in utilizing the several hand levers, care has been taken in this design *not* to lock out the possibility of error. This is important to the educational aspect of the toy since the possibility of error will serve as a direct teaching influence on a child using the toy. For instance, if at the top of a hoist a child merely releases hand lever 102 without at the same time applying the brake lever 80, the load would drop abruptly and, of course, difficulty would be encountered if a swing movement is started by means of hand lever 68 while the hook 48 is engaged with a load but the load is still on the ground.

While certain details of construction have been used herein as a basis for this disclosure, it is clear that many of the details may be varied at the will of the designer. Accordingly, this invention is not to be limited to the precise details of the disclosure but only as set forth in the subjoined claims.

What is claimed is:

1. A toy on which a child may sit while activating various instrumentalities from the sitting position, said toy comprising: a base portion; a platform rotatably mounted on said base portion; a shaft mounted for continuous rotation on said platform; a child's seat on said platform contiguous to said shaft; a boom projecting from said platform; a hoisting drum on said platform having a hoisting line passing over a pulley on said boom; a pair of drive wheels mounted on said platform and engaging said base member to rotate said platform relative to said base member; a lever within reach of said seat for optionally connecting said drum to said shaft for driving said drum; and a second lever contiguous to said first lever, said second lever acting in one position to connect one of said drive wheels to said shaft and in another position to connect the other of said drive wheels to said shaft.
2. A toy as set forth in claim 1, including pedals for driving said shaft.
3. A toy as set forth in claim 1, including a third handle for operating a brake for said drum.
4. A toy as set forth in claim 1, in which said base portion is mounted on wheels.
5. A toy as set forth in claim 4, including pedals for driving said shaft.
6. A toy as set forth in claim 5, including a third handle for operating a brake for said drum.
